UNITED STATES PATENT OFFICE.

WALTER E. SANDS, OF FANWOOD, NEW JERSEY.

MEANS FOR SECURING JUNCTION-BOXES IN CEILINGS AND WALLS.

1,171,751.

Specification of Letters Patent. Patented Feb. 15, 1916.

Application filed October 19, 1914. Serial No. 867,338.

To all whom it may concern:

Be it known that I, WALTER E. SANDS, a citizen of the United States, and residing at Fanwood, in the county of Union and State of New Jersey, have invented certain new and useful Improvements in Means for Securing Junction-Boxes in Ceilings and Walls, of which the following is a specification, such as will enable those skilled in the art to which it appertains to make and use the same.

This invention relates to devices or means for securing junction or outlet boxes in, or to the ceilings and walls of buildings, and the object thereof is to provide an improved device of this class which is comparatively inexpensive and which may be conveniently and easily used or applied; and with this and other objects in view the invention consists in a device of the class specified, constructed and operated as hereinafter described and claimed.

The invention is fully disclosed in the following specification, of which the accompanying drawing forms a part, in which the separate parts of my improvement are designated by suitable reference characters in each of the views, and in which:—

Figure 1 is a section through a part of a floor and ceiling construction and showing my improvement and the method of its use, part of the construction being in section; Fig. 2 a similar view showing the method of using my improvement in a vertical wall construction; Fig. 3 a perspective view of the main part of my improvement detached and, Fig. 4 a partial section on the line 4—4 of Fig. 1.

In the drawing forming part of this specification, reference being made to Fig. 1, I have shown a part of a floor and ceiling construction involving two parallel beams *a* on which is laid a floor *b* and to which is secured a ceiling *c* and, in the practice of my invention, I provide a junction box securing device *d* which, in the construction shown, involves a yoke-shaped member having two diverging arms or side members *d*² and *d*³ connected at *d*⁴, and the arm *d*² is provided at its free end with a foot piece *d*⁵ at right angles thereto and in which are formed holes *d*⁶, and the arm *d*³ is pointed at its free end as shown at *d*⁷. I also mount on one of the arms *d*²—*d*³, preferably the arm *d*³, a stud screw *e* which may be adjusted longitudi-

nally of said arm and secured in any desired position by means of a set screw *e*², and the head portion of said screw is provided with laterally directed wings *e*³ having holes *e*⁴ through which, in practice, the electric wires are passed, and said wings form supports and guides for said wires which are passed into the junction box *f* in the usual manner, but as these wires and method of using them form no part of this invention they are not shown.

In the use of this device the stud screw *e* is passed through the junction box, as clearly shown in Fig. 1, and said screw is provided within the box with a nut *g* and the back of the box with a collar or washer *g*² to strengthen the same, and in this manner the junction box may be secured in the ceiling construction, as will be readily understood, and the projecting portion *e*⁵ of the stud screw *e* may be used for the purpose of attaching or securing any kind or class of an electrical attachment or fixture.

In securing the device *d* to one of the beams *a*, the yoke-shaped part is held with the separate arms in the same vertical plane and a hammer is used on the end *d*⁴ to drive the pointed end *d*⁷ of the arm *d*³ into the beam and nails *h* are driven through the holes *d*⁶ and the foot *d*⁵, and the arm *d*³ serves as a brace for the arm *d*² and the device is thus easily and quickly secured in position.

In Fig. 2 of the accompanying drawing, I have shown at *i* two of the vertical beams of a wall construction and the method of using my junction box holder or support therein, and in this case also the separate arms *d*² and *d*³ of the device are in the same vertical plane, and said device is attached to one of the beams *i* in the same manner as in Fig. 1. In the use of this form of the device, however, the stud screw *e* projects outwardly instead of downwardly as in Fig. 1, and said stud screw passes through the lath and plaster which forms a part of the wall construction and the junction box is mounted on said screw in said lath and plaster construction and flush therewith.

In both forms of construction, the yoke-shaped member of the support is so placed that the arms thereof are in a vertical plane, but this is not necessary and in the ceiling construction the yoke-shaped part of the device may be so placed that the arms thereof

will be in a horizontal plane, and this method of using the device will be preferable when the ceiling construction, or the beams *a* thereof are of slight vertical dimensions.

My invention is also not limited to the use of the stud screw *e* as means for securing the junction box to the yoke-shaped part of the device, and other forms of attachment adapted to be connected with and adjusted longitudinally of the yoke-shaped part of the device may be employed, and the form and construction of the yoke-shaped part of the device may also be varied, and changes in and modifications of the details of the construction herein described may be made, within the scope of the appended claims without departing from the spirit of my invention or sacrificing its advantages.

Having fully described my invention, what I claim as new and desire to secure by Letters Patent, is:-

1. A support for junction boxes, comprising a yoke-shaped device having diverging side arms one of which is provided at its free end with a laterally directed foot member, the other arm being pointed at its free end, and a junction box attaching device

adjustable longitudinally of said yoke-shaped device.

2. A support for a junction box, comprising a yoke-shaped device adapted to be secured to one of the beams of a ceiling or wall construction and to project horizontally in the direction of an adjacent beam and an attaching device for junction boxes mounted on said yoke-shaped device and adjustable longitudinally thereof, or toward and from the adjacent beam.

3. A support for junction boxes, comprising a yoke-shaped device having diverging side arms one of which is provided at its free end with a foot member, the other arm being pointed at its free end, and a junction box attaching and wire supporting device adjustable longitudinally of said yoke-shaped device.

In testimony that I claim the foregoing as my invention I have signed my name in presence of the subscribing witnesses this 16th day of October, 1914.

WALTER E. SANDS.
